DETACHABLE HANDLE FOR A BEVERAGE CAN OR THE LIKE

Russell M. Brown, 56 Holliston Road,
Medway, Mass. 02052

Filed July 17, 1972, Ser. No. 272,302

Term of patent 14 years

Int. Cl. D7—06

U.S. Cl. D7—70

FIG. 1 is a side view of a detachable handle for a beverage can or the like showing my new design;

FIG. 2 is a left end view thereof;

FIG. 3 is a sectional view taken along lines 3—3 of FIG. 1; and

FIG. 4 is a sectional view thereof taken along lines 4—4 of FIG. 1.

I claim:

The ornamental design for a detachable handle for a beverage can or the like, substantially as shown.
